(57) **CLAIM**

The ornamental design for a longhorn style ornament, as shown and described.

DESCRIPTION

The design is embodied in an ornament that may serve, as but a few examples, as a piece of jewelry (as on a necklace, as but one example), or as a clothing accessory (a belt buckle, as but one example).

FIG. 1 is a front view of a longhorn style ornament showing my new design;

FIG. 2 is a back view;

FIG. 3 is a top view;

FIG. 4 is a bottom view;

FIG. 5 is a left side view;

FIG. 6 is a right side view; and,

FIG. 7 is a front perspective view.
